WILLIAM W. LASKER, OF BROOKLYN, NEW YORK, ASSIGNOR, BY MESNE ASSIGNMENTS,
TO REMINGTON RAND INC., OF NEW YORK, N. Y., A CORPORATION OF DELAWARE

ADDING MACHINE

Application filed July 23, 1925. Serial No. 45,576.

The present invention relates to adding, accounting, tabulating or any other machine of a kindred nature, and relates more particularly to the accumulating or total mechanism of such a machine or machines.

Some of the objects of the present invention are to provide an improved accumulating and total mechanism for adding, tabulating and accounting machines; to provide means for varying an accumulating mechanism at will to function in response only to predetermined columns of perforated record cards; to provide an accumulating mechanism having flexibility of control as an advantageous characteristic; to provide means for splitting an accumulating mechanism into operative and inoperative groups at will; to provide means whereby a group in a totalling mechanism can be enlarged at will for accumulating and totalling; and to provide other improvements as will hereinafter appear.

In the accompanying drawings Fig. 1 represents a fragmental section in elevation 25 of a machine equipped with a number carrying bar lock mechanism embodying one form of the present invention; Fig. 2 represents a plan in part section of the number bars and the locking mechanism therefor; Fig. 3 represents a front elevation, in part broken away, of the bar locking mechanism; Fig. 4 represents an enlarged detail of one of the bar latches and its adjuncts in unlatched position; and Fig. 5 represents the same with the 35 latch in latch locked position.

Referring to the drawings, one form of the present invention is shown as applied to an adding machine 10 of the type controlled by perforated record cards 11 which are fed one by one from a hopper 12 by means including feed rolls 13 to registering position upon a perforated plate 14 between spring pressed stop pins 15 and spring pressed analyzing pins 16 of the reciprocable pin box 17. After 40 an analyzing operation with its accompanying set-up of a stop pin 15 in a row of the pins 15, the card 11 is fed by rolls 18 to the receiving magazine 20. In this type of machine each row of the stop pins 15 is above 45 and alined with a reciprocable arm 21 hav-

ing a stop 22 which is arranged to abut the set pin 15 of the row when it is automatically released to the action of its spring 23. The arms 21 are respectively connected to number or digit bars 24, each of which has a digit strip 25 on one edge and a rack 26 on its opposite edge, the former serving to bring the selected digit beneath a sight opening 27 in a plate 28, and the latter to roll in an accumulation on the pinions 30 of the accumulating mechanism 29. The arms 21 are pivoted to the bars 24 on staggered pivots 50 and each of them has a depending arm to which is connected one of the springs 23. The tension of these springs is mainly exerted to draw the bars 21-24 leftward in Fig. 1, but they also tend to swing the bars 21 upward about their pivots 50. The stop lug 22 on each bar 21 normally engages a shoulder of the lower plate 51 in which the pins 15 are guided. 50 When any one of these pins is depressed it pushes the bar 21 downward so that it releases it from the said shoulder.

The bars 24 are operated by a transverse bar 24' which reciprocates left and right in Fig. 1 in a manner well-known in the art. After the pins 15 have been set and the corresponding bars 21 released, then when the bar 24' moves leftward the bars 24 all follow it as far as the pins 15 will permit. The 55 register pinions 30 are disengaged during this operation, but are re-engaged with the racks 26 just before the return stroke of the bar 24' so that the numbers represented by the pins 15 and corresponding to the perforations in the card will be added on the register wheels.

The totals indicated on the register wheels may be read in a manner well understood in adding machines. In some such machines 60 the register pinions bear the ten digits which can be read directly. In the form of the invention shown in the drawings the wheels are not readily visible but can be read after the ordinary manner of taking totals in these 65 machines. The register wheels can first be moved into engagement with the racks as shown in Fig. 1 and all of the bars 21 can be released by any suitable means. On an operation of the operating mechanism of the 70

machine the bar 24' will move forward and allow all the bars 24 to be moved forward by their springs 23. Each bar will then be arrested by the transfer lug 52 of its register wheel striking the abrupt face 53 of the transfer dog 54. The numbers indicated by the register wheels can then be read through the sight opening 27 and can be recorded. If now the register wheels be depressed to their lower position before the bar 24' is restored to its normal position all of the register wheels will be left at zero.

Mechanism suitable for carrying out these operations is familiar in adding machines and is only conventionally shown here.

In this type of machine, whether a simple adding machine, an accounting machine, or a printing tabulator, there are generally as many number bars 24 as there are columns 20 on the record card so that every column perforation causes its bar 24 to indicate the digit corresponding to the perforation, all of which is understood in the art and need not be here further described. Such machines of the 25 prior art, however, operate whenever a perforation appears in a card and each field of the card functions and operates as a separate unit upon its section of the adding mechanism and it is impossible to effect any variation from such operation.

It is often desirable to make variations in the card field arrangement so that a variable number of columns can be thrown together for combination adding, or it may be desirable to omit a field entirely by rendering its 35 adding section ineffective, and to that end the present invention overcomes the disadvantages of prior machines and gives a highly desirable flexibility so that adding can take 40 place to accord with the arrangement desired or with the arrangement of the fields of special or any other cards.

For the purpose, therefore, of splitting up the numeral bars 24 into sections according 45 to any given arrangement within the limits of a record card, each number bar 24 is provided at its otherwise free end with a latch 31 pivoted at 32 thereon and having a release arm 33 extended over and resting upon a 50 restoring rod 34 which is common to all of the arms 33. Each latch 31 lies in the path of the inclined face 35 of a catch 36 on a lock detent 37 which is slidably mounted on and through a fixed angle strip 38 mounted across 55 the end of the machine 10 so that the projecting ends of the detents 37 are readily accessible for manual actuation.

As a means for retaining the latch detents 37 in either of their two positions, each is 60 provided with two edge notches 40 and 41 for cooperation with a locking plate 42 which is attached to the vertical face of the strip 38 by studs 43 fixed to the strip 38 and passing respectively through slots 44 of the plate 42 65 and so inclined that movement of the plate 42

to the right as seen in Fig. 3 will cause the plate to lift out of engagement with the notches 40 or 41 of all of the detents. One end of the plate 42 is outwardly turned to form a thumb-piece 45 for readily releasing 70 the plate 42, and a spring 46 is stretched between a fixed pin 47 and the piece 45 to return the plate 42 to its locking position.

When all of the bars 24 are free to respond to the setting up action of the analyzer all 75 of the detents 37 are in unlocked position, that is, each is in the position shown in Fig. 4 and is held by reason of the locking plate 42 seating in the notch 40. When it is desired to throw certain of the bars 24 out of use the 80 detents 37 for such bars are released by first drawing the plate 42 endwise to lift it out of the detent notches 40, and then those selected 85 detents 37 are pushed in to first raise their latches 31 so that they then can drop back of the catches 36 to hold the selected bars 24 and prevent them from responding to an analyzing step. In this position the locking plate 42 seats in the notches 41 of the set detents 37 and rigidly locks the parts against movement. Thus, while the analyzing unit functions from the record on the perforated card, 90 the bars 24 only register a total for those bars which have been set-up.

In order to release the set latches 31 from 95 the catches 36, the restoring rod 34 is mounted between angle arms 48 which are pivoted at 49 and when swung upward acts upon the release arms 33 to withdraw the latches 31 100 from the catches 36 so that the detents 37 can be pulled to inoperative position when the lock plate 42 is lifted out of the notches 41 and is returned to engage notches 40 to lock the detents in inoperative position.

From the foregoing it will be apparent by 105 the present invention that the number registering or total bars of a machine of this character can be split up into fields to accord with certain predetermined perforated data on the cards and as a result only those total 110 bars selected in the set-up are operative for the desired purpose, and while the functioning of the analyzing unit takes place irrespective of the total bar set-up, totals are only 115 obtained for the fields or groups, or combinations of fields or groups as selected by splitting the total bars in the manner predetermined through the use of the detents 37. By 120 this arrangement it will also be evident that the number of rack bars 24 can not only be increased at will to accord with an increase of the columns in a field of the card but also increased for accumulating and carrying over where the total is certain to exceed in length 125 the ordinary number of bars 24 for such group.

It may be worth while to give one instance 130 to illustrate the manner in which this mechanism can be used. The perforated cards usually have one field or zone devoted to perfora-

tions to indicate group designations and when the cards are run through a machine of the character above described the cards have usually been sorted so that all of the cards of a certain group are together and are fed one after another through the machine.

The operator may set to operative position the catches 36 in the designation zone. When the first card of a group is analyzed the bar 34 10 may be raised allowing the group designation to be entered on the register wheels along with the other numbers. Soon after the bar 24' begins its first stroke the bar 34 may be dropped to its normal position. On the return stroke of the bar 24' the bars 24 of the designation zone will all be automatically relocked by their latches 31 snapping in behind the catches 36 when the bars are restored to normal or home position. The effect of this 15 will be that the group designation will be added on the register wheels but once and will remain there until the cards of that group have all been analyzed and the operator of the machine is ready to read the totals. 20 When setting the machine for reading the totals as above described he will also operate the bar 34 so that the designation will appear in its proper place in the sight opening 27 along with all the other numbers to be copied 25 from the registering mechanism.

It will be seen that this mode of operation is rendered possible by reason of the fact that the latches 31 are so arranged and controlled that they can all be released at once by a 30 common means and so that upon the restoration of the bars 24 they will automatically be caught again.

While only a single form is shown in which this invention may be embodied, it is to be understood that the invention is not limited 40 to any specific construction, but might be applied to various forms without departing from the spirit of the invention or the scope of the appended claims.

Having thus described my invention, I claim:

1. In a machine of the class described, the combination of a plurality of adding racks, settable stops for controlling the extent of 50 differential movement of said racks in adding operations, means for preventing control of any of said racks by their stops in adding operations, and means superseding said preventing means to permit all of said racks to 55 be controlled by their stops.

2. In a machine of the class described, the combination of a plurality of adding racks, settable stops for controlling the extent of movement of said racks in adding operations, 60 retaining means for each rack operable individually for retaining any rack in its home position during an adding operation, common means for simultaneously locking certain of said retaining means in their functioning position and others in their non-func-

tioning position, and means for disabling said retaining means locked in functioning position.

3. In a machine of the class described, the combination of an adding rack, a latch pivoted thereon, and a slidable catch adapted in its operated position to engage said latch, and means for moving said latch out of engagement with said catch.

4. In a machine of the class described, the combination of adding racks, latches pivoted thereon, catches for said latches selectively and individually operable, and a common disabling means for moving all of said latches out of cooperative relation with their catches.

5. In a machine of the class described, the combination of adding racks, latches pivoted thereon, catches for said latches selectively and individually operable, a common disabling means for moving all of said latches out of cooperative relation with their catches, and means on the catches and latches facilitating re-engagement therebetween after said common disabling means is moved into its non-functioning position.

6. The combination with card sensing means and tabulating mechanism controlled thereby and including a series of differentially movable members, of means settable at will to latch particular ones of said differential members against operation, means common to all of said latching means for releasing them for an operation of the machine, and means for automatically re-latching said released means.

7. In a machine of the class described, the combination of adding racks, mechanism settable so as normally to cause an operation of said racks to add numbers, selectively and individually settable means for retaining said racks against adding movement even though said mechanism would otherwise have caused an operation of them, and a single means for disabling all of the first recited means during an operation of the machine, the functioning 100 of the first means being resumed after the disabling means has been returned into non-functioning position.

Signed at New York, county of New York, State of New York, this 13 day of July, 1925.

WILLIAM W. LASKER.
